UNITED STATES PATENT OFFICE.

ERVIN D. SWAN, OF GLEN RIDGE, NEW JERSEY.

CABLEWAY.

1,074,140.

Specification of Letters Patent. Patented Sept. 30, 1913.

Application filed February 12, 1912. Serial No. 677,181.

To all whom it may concern:

Be it known that I, ERVIN D. SWAN, a citizen of the United States, residing at Glen Ridge, in the county of Essex and 5 State of New Jersey, have invented certain new and useful Improvements in Cableways, of which the following is a specification.

My invention relates to new and useful improvements in cableways, and more particularly to means for adjusting and maintaining the proper deflection of the main cable of a cableway, one of its objects being to provide means whereby the cable may be readily and quickly adjusted without stopping the operation of the cableway, and without disturbing the supporting means or connections for the main cable or other ropes of the cableway.

The invention consists in the construction 20 and improvements to be fully described hereinafter, and the novelty of which will be particularly pointed out and distinctly claimed.

I have fully and clearly illustrated my 25 invention in the accompanying drawings to be taken as a part of this specification, and wherein,

Figure 1 is a view in elevation of one embodiment of the invention associated with 30 a portable cableway apparatus; Fig. 2 is a view in elevation of another embodiment of the same invention applied to a portable apparatus; Fig. 3 is a similar view of another embodiment of the same invention.

Referring to the drawings by characters of reference, and particularly to Fig. 1: before describing my invention I desire to state that the same is not to be limited to any particular type of cableway, or to a 40 cableway employed for any particular purpose, although I contemplate using it in connection with a cableway for logging, in which connection it is hereinafter described.

1 designates the base or platform of a portable power apparatus of a logging system, which may travel on wheels 2, and upon which platform is supported a vertical head tower 3 for supporting one end of a cableway, the construction of, and the manner 50 of supporting this tower being immaterial so far as my present invention is concerned, although it may be connected at its base to the platform by a ball and socket connection 4, and be held erect by guys 5. Mounted on the platform may be a hoisting

engine E including drums 6, 7 and 8 for operating and controlling the operating ropes 9, 10, 11 of the cableway, passing over blocks 12, 13, 14 on the tower 3. Mounted on the head of the tower are upper and lower 60 rope guides shown for the purposes of this application as consisting of sets of sheaves 15, 15, and 16, 16, there being two in each set, and spaced vertically from each other, and over the upper faces of the sheaves 15, 65 15 of the upper set passes the main cable 17 of the cableway, said cable having an extension 17^a extending in rear of the tower 3, and passed around a block 18 connected to a split or walking anchorage comprising 70 spreader lines 19, at the point of union of said lines, the opposite ends of which may be anchored to stumps or stakes, not shown. From the block 18 the main cable extension is doubled upon itself and carried over the 75 lower set of pulleys 16, 16, on the head tower, whence said rope extends down the tower over tensioning and guide sheaves 20, 21, and under a block sheave 22, from which point it extends to and is wound on the 80 drum 23 of a winding engine E'. By this arrangement of the main cable, the position of the latter may be adjusted at any time to the proper catenary, and any sag which may occur while the cableway is being 85 operated, may be conveniently and quickly taken up by winding the main cable on the drum 23.

In the embodiment shown in Fig. 2, substantially the same arrangement is shown 90 as in Fig. 1, except, however, the lower set of sheaves 16, 16, are omitted and a block 24 substituted therefor, and a block 25 is employed instead of the sheaves 20, 21, 22, the cable passing over said block 24, thence 95 down through the block 25 to the drum of the winding engine. The operation of this form is the same as that of the embodiment shown in Fig. 1.

In Fig. 3 is illustrated an embodiment in 100 which the head tower is not carried upon the platform 1, but may consist of a tree, stump, or separate tower 26, off the platform, in which case the tree is provided at its upper portion with a block 27, over which 105 passes a rope section 28, connected at one end to the split walking anchorage 29, and carrying at its opposite end on the opposite side of the block 27 from the anchorage a sheave 30, over which the main cable 31 110

passes. From the sheave 30, the main cable extends down the head tree and over a block or sheave 32, at the base of said head tree, from which point said cable is wound on 5 the drum 33 of a hoisting engine. The general principle of construction and operation in this form of the same invention is the same as for the two forms above described.

What I claim and desire to secure by Letters Patent of the United States is:

1. In a cableway, an elevated support, a main cable, an anchorage rope, a sheave on the anchorage rope, means for supporting the main cable on the support, said main 15 cable being looped about said sheave, and a winding drum for operating on said main cable.

2. In a cableway, an elevated support, a cable, an anchorage, a rope guide on the 20 anchorage over which the cable passes, a rope guide at the base of the support over which the cable passes from the first-named guide, a winding drum for the cable, and means for supporting the cable on the said 25 support.

3. In a cableway, an elevated support, an anchorage, a rope guide on the anchorage, a cable passing over the support and said 30 guide and doubled upon itself, a second guide on the support at the head portion thereof, a guide at the base thereof, the re-

turn portion of the cable passing over said guides, and a winding drum for the cable.

4. In a cableway, an elevated support, a cable, a split anchorage, a rope guide on the 35 anchorage over which the cable passes, a rope guide on the support below said first-named guide and over which the cable passes from said first-named guide, winding means for the cable, and means for 40 supporting the cable on the said support.

5. In a cableway, an elevated support, a cable, an anchorage, a rope guide on the anchorage, upper and lower rope guides on the support, a cable passing over one of 45 said last-named guides, looped about the guide on the anchorage and then over the other of the guides on the support and winding means for said cable.

6. In a cableway, an elevated support, a 50 cable, an anchorage, a sheave connected to the anchorage, a rope guide on the support, said cable passing over said guide and about said sheave, and a winding drum upon which the cable is wound. 55

In testimony whereof I have hereunto signed my name in the presence of two subscribing witnesses.

ERVIN D. SWAN.
